RAIL COUPLING

Application filed February 12, 1930. Serial No. 427,839.

This invention relates to an improved rail coupling and seeks, among other objects, to provide a device of this character employing means for limiting the parts of the coupling against longitudinal separation in either direction.

Another object of the invention is to provide a rail coupling which will completely surround the meeting end portions of the rails and effectually brace said rails at said meeting end portions.

A further object of the invention is to provide a rail coupling which will be easy to install and which will need no further attention after installation.

Other and incidental objects of the invention not specifically mentioned in the foregoing will appear during the course of the following description.

In the drawings:

Figure 1 is a perspective view of the device in position.

Figure 2 is a fragmentary bottom plan view of the device.

Figure 3 is a vertical sectional view of the device on the line 3—3 of Figure 2, looking in the direction indicated by the arrows.

Figure 4 is an enlarged fragmentary perspective view showing in more detail the mating interlocking scarf joint construction employed between the sections of the coupling.

Referring now more particularly to the accompanying drawings, the numeral 1 indicates in general the meeting end portions of conventional railroad rails.

The improved rail coupling forming the subject matter of the present invention comprises companion chair plate sections 2 and 3 having relatively thick bottom plate sections 4 and 4' seating the base flanges of the rail ends, and side plates or portions 5 abutting the webs of the rails and engaging under the threads thereof. Connecting the bottom plate sections with the side plates are flange engaging portions 6 which cooperate with the bottom plate sections to snugly receive the flange portions of the meeting ends of the rails 1.

As may be seen more clearly in Figures 2 and 4 of the drawings, the ends of the bot-

tom plate section 4 are cut away medially, one from the top and the other from the bottom, to provide recesses 7 having stepped vertical inner walls providing shoulders 8 while the lower portion of the plate section at one end and the upper portion of the plate section at the other end are extended to provide tongues 9 having stepped vertical shoulders 10. The bottom plate section 4' is provided at its ends with recesses 11 and tongues 12 in reverse relation to the recesses and tongues of the plate section 4, the recesses 11 of the plate section 4' being provided with stepped vertical shoulders 13 and the tongues being provided with stepped vertical shoul- 55 ders 14.

As will be readily understood from the foregoing, when the sections 2 and 3 are placed in operative position about the rail ends, as seen in Figure 1, the mating bottom plate sections are, of course, brought into interlocked relation with the shoulders 10 and 14 of the tongues 9 and 12 abutting the shoulders 8 and 13 of the recesses 7 and 11 respectively, whereby flat, uniform upper 70 and lower surfaces will be formed. Furthermore, the sections of the coupling will be limited against relative vertical movement while said shoulders will coact for limiting 75 said sections against relative longitudinal 80 movement.

To place the device in operative position, the sections are first disposed about the meeting end portions of the rail ends with the side plates 5 engaging the webs of the rails and the bottom plate sections interlocking. Bolts 15 are then passed through the side portions 5 and the webs of the rails and tightened, whereby the parts will be firmly held in assembled relation. 85

Having thus described the invention, we claim:

A railroad rail coupling including companion chair plate sections having mating bottom plate sections, one of said bottom plate sections being cut away at its ends medially of its thickness, one end from the top and the other end from the bottom, to provide recesses having stepped shoulders and the remaining portion of the thickness extended to form 95 100

stepped scarf tongues, the other of the bottom plate sections being provided with identical tongues and recesses adapted to cooperate with the tongues and recesses on the first mentioned bottom plate section but disposed in reverse relation thereto whereby the sections will be limited against longitudinal separation in either direction as well as against relative vertical movement.

In testimony whereof we affix our signatures.

THOMAS P. WALTON. [L.S.]
